ELECTRIC SURFACING TOOL

William E. Holt, Livingston, N. J.

Application October 19, 1937, Serial No. 169,792

6 Claims. (Cl. 51—170)

This invention relates to the construction of portable electric surfacing tools capable of high speed sanding and finishing operations on metal, stone and wood surfaces of all types.

5 The main object of my invention is the provision of a tool of the character described having an improved construction and arrangement of its parts, and more particularly, of a dust collection and disposal system for such a tool.

10 The various features of novelty which characterize my invention are pointed out with particularity in the claims annexed to and forming a part of this specification. For a better understanding of the invention, its operating advantages and specific objects attained by its use, reference should be had to the accompanying drawings and descriptive matter in which I have illustrated and described a preferred embodiment of my invention.

20 Of the drawings:

Fig. 1 is an elevation of a surfacing tool constructed in accordance with my invention;

Fig. 2 is a similar elevation with some of the parts broken away and in section;

25 Fig. 3 is a bottom view; and

Fig. 4 is an end view of the tool shown in Fig. 1.

In the surfacing tool illustrated, a sectional housing 10 has a horizontally elongated main section 11 enclosing a high speed electric motor 12, the armature shaft 13 of which is arranged to rotate about a horizontal axis. The housing section 11 has a flange connection at its front end to a rounded end section 14 into which projects the corresponding end of the armature shaft.

30 35 The housing section 14 also encloses gears 15, 16 forming a driving connection between one end of the shaft 13 and a vertical spindle 17, the lower portion of which projects through a dust sealed bearing 18 closing the bottom of the section 14.

40 45 A flexible felt and metal pad 19 is detachably mounted on the spindle to form a cushioning layer for an abrasive disc 20 held against its lower face.

In operation, a considerable amount of dust is 45 generated by the action of the abrasive disc on the surface undergoing treatment, and it is highly desirable that this be efficiently withdrawn from the surfacing zone and collected, not only from a health standpoint but also to avoid its deposition in the motor through the ventilating openings 21 in the housing section 11. For this purpose a frusto-conical dust hood 25 is detachably connected to the underside of the housing section 14 with its lower edge located slightly above the 50 plane of the abrasive disc 20 and an arcuate

portion cut away along its lower front edge to permit tilting of the surfacing element. A flexible dust seal is provided between the surface being treated and the lower edge of the hood 25 over most of its circumference by a row of bristles 26 5 held in position on the hood by a band 27.

The rear side of the hood 25 is formed with a dust outlet 28 opening into a horizontally elongated dust conduit 29 of rectangular cross-section integrally formed with the hood and extending 10 horizontally below the housing section 11 to a point beyond the rear end of the motor. On the rear end of the conduit 29 is a circular extension 30 which is utilized as a fan chamber 31. The chamber 31 is separated from the space occupied 15 by the motor by its vertical front wall 32 detachably connected to a dust sealed bearing 33 closing the rear end of the housing section 11, the rear end of the armature shaft 13 extending 20 through the bearing 33 and wall 32 into the fan chamber. An exhaust fan 34 is mounted on the shaft 13 in the fan chamber. Communication between the rear end of the conduit 29 and the rear side of the fan chamber is maintained by 25 a hollow closure section 31. The dust-laden air withdrawn from the hood 25 through the conduit 29 by the fan 34 is discharged from the fan chamber through a top outlet 38, to which a dust bag 39 is normally tied, as indicated in Fig. 1.

30 The power supply line to the motor includes a pair of leads 40 connected to a switch box 41 in a pocket 43 on the rear end of the closure member 31. Electric power is supplied to the switch box 41 through a conductor cable 44 extending 35 through a handle 45 on the rear end of the tool. An additional handle 46 can be secured to either side of the housing section 14 for the other hand of the operator.

The described construction provides a high speed surfacing tool which is of light weight compact construction, convenient to handle and operate, of relatively low cost construction, and readily accessible for inspection and repairs. The horizontal arrangement of the motor and its location 40 laterally offset from the dust generating zone 45 has proved particularly effective in operation in maintaining it in an operative condition. The dust collecting system adds little to either the size or weight of the tool and provides complete protection for the parts requiring protection 50 from abrasive dust and dirt, as well as eliminating a serious nuisance to the operator.

While in accordance with the provisions of the statutes I have illustrated and described herein 55 the best form of my invention now known to me,

those skilled in the art will understand that changes may be made in the form of the apparatus disclosed without departing from the spirit of the invention covered by my claims, and that 5 certain features of my invention may sometimes be used to advantage without a corresponding use of other features.

I claim:

- 10 1. A portable surfacing tool comprising an electric motor having a horizontally arranged armature shaft, a vertical spindle at one end of said armature shaft and having a surfacing element on its lower end, and gearing operatively connecting said armature shaft and spindle, a dust hood surrounding said surfacing element, a fan chamber at the opposite end of said armature shaft, an exhaust fan in said chamber, and a dust conduit extending below said motor and connecting said dust hood and fan chamber.
- 15 2. A portable surfacing tool comprising a housing enclosing an electric motor having a horizontally arranged armature shaft, a vertical spindle at one end of said armature shaft and having a horizontally rotatable surfacing element on its lower end, and gearing operatively connecting said armature shaft and spindle, a dust hood at one end of said housing and surrounding said surfacing element, a fan chamber at the opposite end of said armature shaft, an exhaust fan in said chamber mounted on said armature shaft opposite end, and a dust conduit extending below said motor and connecting said dust hood and fan chamber.
- 20 3. A portable surfacing tool comprising a housing enclosing an electric motor having a horizontally arranged armature shaft, a vertical spindle at one end of said armature shaft and having a horizontally rotatable surfacing element on its lower end, and gearing operatively connecting said armature shaft and spindle, a circular dust hood at one end of said housing and surrounding said surfacing element, a fan chamber enclosing the opposite end of said armature shaft, an exhaust fan in said chamber mounted on said armature shaft opposite end, and a horizontally arranged dust conduit extending below said motor and connecting said dust hood and fan chamber, said dust hood and conduit being detachably connected to said housing.
- 25 4. A portable surfacing tool comprising a housing enclosing an electric motor having a horizontally arranged armature shaft, a vertical spindle at one end of said armature shaft and hav-

ing a surfacing element on its lower end, and gearing operatively connecting said armature shaft and spindle, a dust hood at one end of said housing and surrounding said surfacing element, a fan chamber at the opposite end of said armature shaft, an exhaust fan in said chamber mounted on said armature shaft opposite end, a dust conduit extending below said motor and connecting said dust hood and fan chamber, a switch box mounted adjacent said fan chamber, 10 and handles mounted on said switch box and the opposite end of said housing for manipulating said tool.

5. A portable surfacing tool comprising a housing enclosing an electric motor having a horizontally arranged armature shaft, a vertical spindle at one end of said armature shaft and having a horizontally rotatable surfacing element on its lower end, and gearing operatively connecting said armature shaft and spindle, a circular dust hood at one end of said housing and surrounding said surfacing element, a fan chamber at the opposite end of said armature shaft, an exhaust fan in said chamber mounted on said armature shaft opposite end, a horizontally arranged dust conduit extending below said housing and connecting said dust hood and fan chamber, a switch box mounted adjacent said fan chamber, and handles mounted on said switch box and the opposite end of said housing for 30 manipulating said tool.

6. A portable surfacing tool comprising a housing enclosing an electric motor having a horizontally arranged armature shaft, a vertical spindle at one end of said armature shaft and having a horizontally rotatable surfacing element on its lower end, and gearing operatively connecting said armature shaft and spindle, a circular dust hood detachably connected to the under side of one end of said housing and surrounding said surfacing element, said dust hood having an integral conduit extension arranged below said motor, a fan chamber above the end of said conduit extension, an exhaust fan in said fan chamber mounted on the opposite end of said armature shaft, an end closure member connecting said dust hood conduit extension and said fan chamber, a dust outlet at the upper end of said fan chamber, a dust bag connected to said outlet, and handles mounted on said closure member and the opposite end of said housing for manipulating said tool.

WILLIAM E. HOLT.
